Inventor.

UNITED STATES PATENT OFFICE.

JOHN T. SMITH, OF SAN FRANCISCO, CALIFORNIA.

STEAM OR WATER PACKING.

SPECIFICATION forming part of Letters Patent No. 398,461, dated February 26, 1889.

Application filed March 31, 1888. Serial No. 269,103. (No model.)

To all whom it may concern.

Be it known that I, JOHN T. SMITH, of the city and county of San Francisco, State of California, have invented an Improvement in 5 Steam or Water Packing, to be known as the "Union Coil Packing," and which may be described as follows:

A packing having a central core of suitable fibrous material saturated with a mixture of 10 pulverized soapstone and flour in suitable proportions, a wrapping of perforated rubber or cork inclosing said core, a layer of sheet cotton, and a diagonally-wound wrapper of flax, all inclosed in a plating of slack-twisted cord of suitable fibrous material, substantially as shown 15 and described herein. The central core may be composed of any suitable fibrous material—such as flax, hemp, or cotton—saturated with a preparation of pulverized soapstone and flour, in proportions of four parts of pulverized soapstone to one part of flour, the fibrous material thus saturated being firmly twisted in any size required. This central core is then wrapped, either lengthwise or diagonally, with 20 strips of perforated rubber or cork, varying in thickness from one thirty-second to one-half of an inch. Outside this rubber wrapping is wound diagonally any suitable fibrous material, in thickness from one thirty-second 25 to three-eighths of an inch, or as may be required, this last also lubricated with a suitable proportion of soapstone and flour, as above described. To secure this packing and to complete it to the required size it is plated with a slack-twisted cord of any suitable fibrous material.

The packing may be made round or square, in sizes varying from one-fourth of an inch to two inches in diameter and in any required 40 length.

To prepare this packing for use in circles to suit any size of piston-rods, &c., it should be first dampened and firmly wound around a tube or mandrel of the required size, then

placed in a drying-room until thoroughly 45 dried, when upon being taken from the tube or mandrel it will retain the form desired.

The accompanying drawings more fully explain the invention.

Figure 1 represents the coil as prepared for 50 use, and shows the various materials used in its construction. Fig. 2 represents the transverse section of the same.

C is the central core of fibrous material saturated with a mixture of pulverized soapstone 55 and flour.

R is a perforated rubber or cork wrapping inclosing the central core, around which is wrapped (N) any suitable fibrous material wound diagonally and lubricated, as above described, and F is the slack-twisted cord of 60 fibrous material inclosing the whole.

In Fig. 2, C is the central core of fibrous material; r, the perforated rubber or cork wrapping; n, the fibrous wrapping outside of the 65 rubber or cork; f, the outer cover, as above described.

Having thus described my invention, what I claim as new in construction, and desire to secure by Letters Patent, is—

A packing having a central core of suitable fibrous material saturated with a mixture of pulverized soapstone and flour, as above described, the core being wrapped with perforated rubber or cork to allow the lubricant to 75 pass from the central core to the outer covering, which is composed of a fibrous material saturated as above described, and the whole plated with a slack-twisted cord of suitable fibrous material, substantially the same as 80 above described.

In witness whereof I have hereunto set my hand and seal this 24th day of March, A. D. 1888.

JOHN T. SMITH. [L. S.]

In presence of—

J. F. KINGWELL,
SHELDON G. KELLOGG.
